UNITED STATES PATENT OFFICE.

WALTER HARVEY ZACHRY, OF ATLANTA, GEORGIA.

MOP-HEAD.

957,025.

Specification of Letters Patent.

Patented May 3, 1910.

Application filed December 4, 1909. Serial No. 531,344.

To all whom it may concern:

Be it known that I, WALTER HARVEY ZACHRY, a citizen of the United States, and a resident of Atlanta, in the county of Fulton and State of Georgia, have invented certain new and useful Improvements in Mop-Heads, of which the following is a specification.

My invention is an improvement in mop heads, and consists in certain novel constructions and combinations of parts herein-after described and claimed.

The object of the invention is to provide a device of the character specified, which, while simply constructed, will be efficient, which may be cheaply manufactured, and which will be capable of withstanding rough treatment without much injury.

Referring to the drawings forming a part hereof:—Figure 1 is a perspective view of the improved head. Fig. 2 is a longitudinal section of the head. Fig. 3 is a plan view looking directly down upon the head, and Fig. 4 is a side view of the sleeve.

The embodiment of the invention shown in the drawings consists of a bolt composed of a threaded stem A, and a head B, and the head is provided with a transverse kerf C for receiving a screw driver or like instrument, and at diametrically opposite points, with resilient lateral extensions D and E. The extensions are in the shape of straps and extend outwardly, and are then doubled or bent over upon themselves, as at G, the free ends of the straps lying adjacent to the stem, as shown in Fig. 2.

A canopy or cover plate H, substantially conical in shape, is provided with a central threaded opening at its apex containing one or more threads through which the stem extends, and the bent over portions G of the straps are engaged by the inner face of the cover plate, when the said plate is turned toward the head of the bolt. The outer face of the cover plate is smoothly finished to make a neat appearance, and the said surface is provided at opposite points and near the free edge with projections or bosses I, in order that the plate may be turned on the stem, or prevented from turning when the handle to be described is turned.

The handle K is of any desired or usual construction, and the end of the handle adjacent to the head may or may not be reduced, as at M, to receive a ferrule N. The end of the handle is also provided with an

opening P, and an internally threaded sleeve Q is arranged in the opening. The outer end of the sleeve is laterally flanged, as at Q', and the flange is provided with prongs 60 Q'', which engage the end of the handle to retain the sleeve in place.

The stem A is threaded into the sleeve, and the apex of the cover plate is flat and fits smoothly against the end of the sleeve 65 and the end of the ferrule or handle. The lateral extensions are straight before the first insertion of the mop material.

To insert the material S of the mop, the handle is turned to loosen the bolt, or the 70 bolt may be removed. The material is passed between the bent over portions, and the handle is then turned to tighten the bolt. The extensions being of resilient material, when they engage the inclined inner surface 75 of the cover plate, the sides of the doubled portions are pushed together, thus gripping the material firmly.

To release the material, the motion of the handle is reversed, and the doubled over 80 portions spring upward, thus freeing the material and permitting it to be withdrawn. During shipment, the head may be removed from the handle, and the heads packed in one receptacle and the handles in the other. 85

It will be evident that the improved head, while simply constructed, is efficient, and all the operative mechanism is concealed by the cover plate. When not in use, the parts may be separated, to permit the threads to dry, 90 thus preventing rust, and increasing the longevity of the head.

As an article of manufacture, the device would possibly be marketed without the handle. 95

As before suggested the canopy may contain one or more threads as may be desired and it is not necessary to reduce the handle to receive the ferrule as the ferrule instead of being a long sleeve as shown, may be 100 simply a narrow ring encircling the lower end of the handle to properly brace the same.

I claim:—

1. A device of the class described, comprising a bolt consisting of a threaded stem 105 and a head provided with a transverse kerf, and having at opposite sides of the head resilient lateral extensions, each of said extensions being bent over upon itself to grasp the material of the mop, the free end of the 110 extension being adjacent to the stem, a handle, a ferrule on the handle, said handle

- 5 having a recess in its end, an internally threaded sleeve in the recess for receiving the stem, means on the sleeve for holding it in place, and a cover plate substantially conical 10 in shape and having a threaded opening in its apex through which the stem passes, the bent over portions of the extensions engaging the inner surface of the plate.
- 10 2. A device of the character specified, 15 comprising a bolt having a threaded stem and a head provided with oppositely extending lateral extensions, said extensions being bent over upon themselves toward the stem for the purpose specified, a substantially 20 conical cover plate having a threaded opening in its apex through which the stem passes, the inner surface of the plate engaging the bent over portions, a handle having a recess in the end thereof, and an internally 25 threaded sleeve in the recess for receiving the stem.
- 25 3. A device of the class described, comprising a bolt comprising a threaded stem and a head, said head having oppositely extending resilient lateral extensions, the ends 30 of the extensions being bent over toward the stem for the purpose specified, a handle threaded onto the stem, and a cover plate between the handle and the head of the stem, and having a threaded opening through which the stem passes.
- 30 4. In a device of the class described, a mop head comprising a bolt having a

threaded stem and a head having lateral extensions, the free ends of which are bent 35 over upon themselves toward the stem for the purpose specified, a sleeve having a threaded opening for receiving the stem, and a conical cover plate having a threaded opening through which the stem passes and 40 engaging the extensions with its inner face.

5. A device of the class described, comprising a bolt having a threaded stem and a head provided with lateral resilient extensions, the free ends of the extensions being 45 bent over upon themselves toward the stem for fastening the mop material therebetween, a handle threaded onto the stem, a sleeve in the end of the handle and having a threaded opening for the stem, and means between the 50 sleeve and the head for engaging the said ends to clamp them on the mop material, when the sleeve is turned toward the extensions.

6. In a device of the class described, a mop 55 head comprising a bolt having a threaded stem and a head provided with lateral resilient extensions, the free ends of the extensions being bent over upon themselves toward the stem for clasping the mop material 60 therebetween, and an internally threaded sleeve for receiving the stem.
